His Attorney

UNITED STATES PATENT OFFICE.

CHARLES HENRY NAYLOR, OF RUGBY, ENGLAND, ASSIGNOR TO GENERAL ELECTRIC COMPANY, A CORPORATION OF NEW YORK.

STEAM-ACCUMULATOR.

1,174,602.

Specification of Letters Patent. Patented Mar. 7, 1916.

Application filed November 1, 1915. Serial No. 59,081.

To all whom it may concern:

Be it known that I, CHARLES HENRY NAYLOR, a subject of the King of Great Britain, residing at Rugby, in the county of Warwickshire, England, have invented 5 certain new and useful Improvements in Steam-Accumulators, of which the following is a specification.

The present invention relates to steam accumulators of the expansible receiver type 10 for receiving an intermittent supply of exhaust steam from a reciprocating engine for example, and delivering it at a constant pressure to a point of consumption, as a 15 steam turbine.

The object of the invention is to provide an improved structure which does away 20 with all large heavy moving parts and which provides automatic valve mechanisms 25 for the prevention of over-charging or excessive discharging.

For a consideration of what I believe to be novel and my invention, attention is directed to the following description and the 25 claims appended thereto.

In the accompanying drawing, Figure 1 is a vertical sectional view of an embodiment 30 of my invention; and Fig. 2 is a vertical sectional view of the valve mechanisms.

Referring to the drawing 5 indicates a water tank which may be of concrete or other suitable material and for convenience may be inserted in an excavation in the 35 ground as illustrated. Within this tank is an inverted tank 6 of steel, reinforced concrete, or other suitable material rigidly secured in any convenient manner as for example by means of the standards or columns 7. This tank is open at its lower end 40 so that water can pass freely from the inner to the outer tank and vice versa.

An intermittent supply of steam enters 45 through a conduit 8 and valve casing 9 and passes by way of conduit 10 to the inner tank 6 at some point in the top about the center. The tank 6 thus forms a steam receiving tank which is water sealed. As steam flows into the inner tank, the water 50 is expelled by way of the open space at the bottom of its sides, thus an expansible reservoir is devised, having no large moving parts, the movement taking place in the surrounding water medium. When the accumulator discharges its steam, the water

flows back from the annular space in the outer tank to the inner tank, thus filling the inner tank with water in place of steam. In order to obviate excessive condensation of steam into the water thereby raising its 60 temperature to an unnecessary degree the surface of the water may be covered with a layer of oil or other light non-volatile liquid.

In order to prevent the accumulator from 65 being overcharged on the one hand, and to prevent water from being drawn up into the steam supply pipe on the other hand, a special type of valve mechanism is added as a subsidiary device. Working 70 in conjunction with this valve mechanism is a float 12 sliding on a vertical stem or spindle 13. This valve mechanism comprises a double beat valve 14 having valve seats 15 and it is arranged to move downwardly in opening so as to permit it to open by gravity when there is a vacuum on the conduit 15^a, leading to the turbine or other consumption device. The valve is connected to a vertical tubular sleeve 16 75 which surrounds the spindle 13 and passes through a guide and stop member 16^a which member acts to limit the opening movement of the valve. Connected to the lower end of the sleeve 16 is a tube 16^b the end of 80 which is adapted to be engaged by the float 12. The stem or spindle 13 is prolonged above the valve and connects with a second valve 17 through a slotted link 18 and bell-crank levers 19.

20 indicates an annular seat for valve 17, which valve is in the nature of a relief valve. The lower end of the vertical spindle 13 is guided in a foot-step bearing 21 and has a collar 22 adapted to be engaged 25 by the float 12. The valve 17 is weighted by means of a number of disks 23 so that its normal position is to remain closed, while the valve 14 is normally open.

The operation of the device is as follows: When the water rises in the inner tank 6 to such a height as is deemed safe against the possibility of its rising into the main supply pipe, the float catches against the lower end of tube 16^b which is secured 105 to the tubular valve stem 16 and closes the valve 14 so that no further steam can escape, and consequently the rise of the water ceases. This is of course when the accumulator is fully discharged. When charg- 110

ing takes place and the water descends so low in the inner vessel that there is danger of the oil on its surface being driven out at the annular space at the bottom of its sides, 5 the float then catches against the stop 22 and the slotted link 18 comes against the ends of the bell-crank levers 19 causing the other ends of these levers to open the relief valve 17. The incoming steam is then relieved to atmosphere and the further descent of the water in the accumulator is arrested. This of course is when the accumulator is fully charged.

While the specific means shown for supporting the inner tank is now considered by me as being preferable, it will be understood that my invention is not limited to this arrangement, and that any other suitable means may be used.

20 The volume of the outer tank may be about twice the volume of the inner tank so that when the inner tank is empty, the annular space in the water tank is full to the top. This would occur if the top of the 25 inner tank is on a level with the top of the outer tank. The pressure variation in this case would be from a point below atmosphere to a point above atmosphere, about equal either way. If it is desired that the 30 pressure be constantly above atmosphere in the inner vessel, it would be necessary to fix the inner vessel in such a position in the tank that the top of it is considerably below the top of the outer tank, and the inner 35 tank would always be submerged even when fully discharged and full of water. The whole of the surface of the inner tank should be insulated with some heat non-conducting material which is at the same time water resisting.

40 The above described arrangement, it will be seen, provides a structure in which there are no heavy moving parts and which therefore necessitates no strong guides or wearing parts; at the same time however it provides an efficient automatic mechanism for the prevention of overcharging or excessive discharging.

45 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means, such as come within the scope of the appended claims.

50 What I claim as new and desire to secure by Letters Patent of the United States, is:—

55 1. A steam accumulator comprising a stationary water tank, a fixed inverted steam receiving tank therein, conduit means for conveying steam to and from the receiving tank, and valve mechanism for automatic-

60 cally preventing over-charging and excessive discharging.

2. A steam accumulator comprising a stationary water tank, a fixed inverted steam receiving tank therein, an inlet conduit and 70 an exit conduit for conveying steam to and from the receiving tank, a valve in the exit conduit, and means for closing said valve when the steam has been discharged to a predetermined extent.

75 3. A steam accumulator comprising a stationary water tank, a fixed inverted steam receiving tank therein, an inlet conduit and an exit conduit for conveying steam to and 80 from the receiving tank, a relief valve, and means for automatically opening said valve to prevent overcharging of the accumulator.

4. A steam accumulator comprising a stationary water tank, a fixed inverted steam receiving tank therein, an inlet conduit and 85 an exit conduit for conveying steam to and from the receiving tank, a valve in the exit conduit, a stem connected to it, and a float which engages the stem to close the valve when the water reaches a predetermined 90 high level in the steam chamber.

5. A steam accumulator comprising a stationary water tank, a fixed inverted steam receiving tank therein, an inlet conduit and an exit conduit for conveying steam to and 95 from the receiving tank, a relief valve, a spindle connected to it, and a float which engages the spindle to open the relief valve when the water reaches a predetermined low level in the steam chamber.

100 6. The combination with a steam accumulator comprising a stationary water tank and a fixed inverted steam receiving tank therein, the lower edge of which is sealed by the water, said steam receiving tank having an admission conduit and an exit conduit, of a normally open valve in the exit conduit, a normally closed relief valve in the steam receiving tank, and means controlled by the level of the water in the steam 105 receiving tank for closing the first named valve when such water reaches a predetermined high level and for opening the relief valve when it reaches a predetermined low level.

110 7. A steam accumulator comprising a stationary water tank, a fixed inverted steam receiving tank therein, an inlet conduit and an exit conduit for conveying steam to and from the receiving tank, a relief valve in 120 the steam receiving tank having a stem, a valve in the exit conduit having a stem, and means controlled by the level of the water in the steam receiving tank which engages said stems to open the relief valve and to 125 close the valve in the exit conduit.

8. A steam accumulator comprising a stationary water tank, a fixed inverted steam receiving tank therein, an inlet conduit and an exit conduit for conveying steam to and 130

from the receiving tank, a relief valve in the steam receiving tank having a stem, a valve in the exit conduit having a tubular stem which surrounds the other stem and 5 terminates short of the end thereof, a collar on the first named stem and a float which is guided by such stem and is located between the collar and the end of the tubular stem.

9. A steam accumulator comprising a stationary water tank, a fixed inverted steam receiving tank therein, an inlet conduit and an exit conduit for conveying steam to and from the receiving tank, a relief valve biased to closed position in such tank, a valve

biased to open position in the exit conduit, 15 and a float controlled by the level of the water in the steam receiving tank for opening the relief valve when the steam receiving tank becomes overcharged, and for closing the exit valve when the steam receiving tank becomes over-discharged.

In witness whereof, I have hereunto set my hand this 14th day of October 1915.

CHARLES HENRY NAYLOR.
